UNITED STATES PATENT OFFICE.

DWIGHT C. SUMNER, OF NEW YORK, N. Y.

DESIGN FOR ORNAMENTING CLOTH.

SPECIFICATION forming part of Design No. 12,708, dated January 24, 1882.

Application filed December 27, 1881. Term of patent 3½ years.

To all whom it may concern:

Be it known that I, DWIGHT C. SUMNER, of New York, in the county and State of New York, have invented a new and original Design 5 for Ornamenting Cloth, of which the following is a specification.

The accompanying drawing represents a face view of my new design.

This design relates to a new ornamentation 10 for cloth by means of depressed grooves or furrows. The cloth is ornamented by a series of rectangular fields adjoining each other in such manner as to break joints, as hereinafter described.

15 In the drawing, A represents a piece of cloth ornamented according to my design. Its nap is cut away to form upright grooves *a a* and transverse grooves *b* and *d*, thus producing rectangular fields *e* and *f* in alternating

rows—that is to say, between one pair of upright 20 furrows *a* are transverse furrows *b* and fields *e*. Adjoining these are the fields *f* and transverse furrows *d*; adjoining these, again, fields *e* and furrows *b*, and so on. The furrows *b* break joints with the furrows *d*, as indicated, so that 25 thus the fields *e* and *f* also break joints. The structure of the cloth is seen at the bottom of each groove or furrow.

I claim—

The design for ornamenting cloth, consisting 30 of the parallel grooves or furrows *a a* and transversely-placed furrows or grooves *b* and *d*, which are arranged to break joints, forming fields *e* and *f*, substantially as shown.

DWIGHT C. SUMNER.
